CLAIM

The ornamental design for a vehicle air dam as shown and described.

DESCRIPTION

FIG. 1 is an isometric view of a vehicle air dam, showing an embodiment of our new design.

FIG. 2 is a front elevational view thereof.

FIG. 3 is a left side elevational view thereof.

FIG. 4 is a right side elevational view thereof.

FIG. 5 is a bottom plan elevational view thereof.

FIG. 6 is a top plan elevational view thereof.

FIG. 7 is an isometric view of a vehicle air dam, showing another embodiment of our new design, which is a mirror image of the vehicle air dam shown in FIGS. 1-6.

FIG. 8 is a front elevational view thereof.

FIG. 9 is a right side elevational view thereof.

FIG. 10 is a left side elevational view thereof.

FIG. 11 is a bottom plan elevational view thereof; and,

FIG. 12 is a top plan elevational view thereof.

Stippling and tangency lines in the drawings represent the three-dimensional contours of the design, and are not intended to indicate surface decoration. The broken lines shown in the drawings depict portions of the vehicle air dam that form no part of the claimed design.
